UNITED STATES PATENT OFFICE.

LOUIS F. SECORD AND BENJAMIN ORR, OF JACKSON, MICHIGAN, ASSIGNEES TO
WHITMAN AGRICULTURAL CO., OF ST. LOUIS, MISSOURI.

INTERNAL-COMBUSTION ENGINE.

1,082,656.

Specification of Letters Patent.

Patented Dec. 30, 1913.

Application filed June 15, 1912. Serial No. 703,816.

To all whom it may concern:

Be it known that we, LOUIS F. SECORD and BENJAMIN ORR, citizens of the United States, residing at the city of Jackson, county of Jackson, State of Michigan, have invented certain new and useful Improvements in Internal-Combustion Engines, of which the following is a specification.

This invention relates to improvements in 10 internal combustion engines.

The object of this invention is to provide an improved hopper cooled engine in which the valves shall be readily accessible for inspection and repair and adjustment, and also 15 shall be easily assembled, and shall not be exposed to the direct action of the cooling medium in the hopper or jacket.

Objects relating to mere details will 20 definitely appear from the detailed description to follow.

We accomplish the objects of our invention by the devices and means described in the following specification.

The invention is clearly defined and 25 pointed out in the claims.

A structure constituting a preferred embodiment of our invention is clearly illustrated in the accompanying drawing, forming a part of this specification, in which—

30 Figure I is a perspective view of an internal combustion engine embodying the features of our invention. Fig. II is an enlarged detail vertical sectional elevation taken on a line corresponding to line 2—2 of Figs. I and III. Fig. III is an enlarged detail sectional view taken on a line corresponding to line 3—3 of Fig. II. Fig. IV is an enlarged detail sectional view taken 35 on a line corresponding to line 4—4 of Figs. II and III.

In the drawing, all of the sectional views are taken looking in the direction of the little arrows at the ends of the sectional lines, and similar numerals of reference 40 refer to similar parts throughout the several views.

Referring to the lettered parts of the drawing, the engine is of the usual construction of gasoline engine, having a base 1 and a cylinder 2, a water jacket 3 open at the top around the head of the cylinder and provided with a hopper 4. The hopper 4 is provided with an external recess 4' in the

exterior of its casing, for the accommodation of the valves and their springs. A 55 port 6 leads to the valve chamber 5, into which opens the intake valve 7 which is provided with the spring 8. An exhaust valve 9 opens into the exhaust passage 11, and is held to its seat by the spring 10. Any 60 usual means are provided for operating the valve, and as our invention does not pertain to the same, we have not here illustrated any means for actuating the exhaust valve. A supply passage 12 from the carburetor 65 14 is suitably flanged and connected by cap-screw 13, and a pipe 15 is disposed in the passage or aperture 16 through the hopper 4. See Figs. III and IV. A spark plug 17 is provided at the valve chamber 6. A suitable muffler 18 may be provided. 70

The different parts of our engine, as the valve, muffler and carburetor are of the usual construction, and we do not show details of the same here as they are of any usual or 75 desired construction. Our invention pertains to the particular arrangement of the cooling hopper and the formation whereby the valves are accessible.

We desire to claim our invention broadly 80 and specifically, as indicated in the appended claims.

Having thus described our invention, what we claim as new and desire to secure by Letters Patent is:

1. In an internal combustion engine, the combination with the upright cylinder, of a suitable water jacket open at the top, a cooling hopper connected by suitable flanges to the said water jacket and having a recess formed in the wall thereof to accommodate the valves and having a lateral aperture through which connection to the carburetor is made, a valve and valve casing and feed connection disposed in said recess in spaced 90 relation to the wall of said hopper coacting as described for the purpose specified. 85

2. In a water cooled engine, the combination with the engine cylinder with jacket open at the top and a cooling hopper, connected by suitable flange thereto with a recess in the wall thereof to accommodate the valves of the engine, and a valve with casing disposed in said recess in spaced relation to said hopper wall, as specified. 100

3. In a water cooled engine, the combina-

tion with the engine cylinder with jacket open at the top and a cooling hopper, with a recess in the wall thereof to accommodate the valves of the engine, and a valve with casing disposed in said recess in spaced relation to said hopper wall, as specified.

In witness whereof, we have hereunto set

our hands and seals in the presence of two witnesses.

LOUIS F. SECORD. [L. S.]
BENJAMIN ORR. [L. S.]
